UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

WEB CONTROLLING APPARATUS

Application filed July 14, 1927, Serial No. 205,719. Renewed September 18, 1931.

This invention relates to the supply of a printing press with a web of paper.

The principal objects of the invention are to provide means for controlling the speed of the web from the running roll to the press when the press either stops or slows down; to provide means whereby the web, coming directly from the running roll, will run at the proper speed normally without any assistance, and will be slowed down in proportion to the reduced speed of the press when stopping; and to provide mechanism by which the press will run the web controlling means only when the press is running at less than full speed and the said web controlling means will be run by the web at all other times.

Other objects and advantages of the invention will appear hereinafter.

Reference is to be had to the accompanying drawings, in which

Fig. 1 is a side view of part of a printing press, showing a preferred embodiment of this invention; and

Fig. 2 is an end elevation of the same.

In web replenishing devices of a certain type, the web rolls are mounted on a rotary reel in such position that the fresh roll comes around close to the web running from the active roll and the paster is made when the fresh roll and the web are adjacent to each other. In these machines, as so far designed, the web going to the press is propelled by feed belts which are connected positively with the press and operated at web speed and engage the web on the surface of the rotating roll. Thus these belts propel this roll and keep the web up to speed in accordance with the speed of the press. I have discovered that the propelling of this roll positively in this way is unnecessary and in fact adds a complication to this type of machine. This invention relates to a device for holding back the running web roll and the web, under certain circumstances. The actual propelling of this running roll is not accomplished by the mechanism of this invention, except by the pull on the web from the press.

For this purpose I provide the usual rotary reel 10 with the fresh roll 11 shown nearly in pasting position and the running roll 12

in running position. The parts operate in this way until the running roll is reduced down nearly to the stub and then the web and fresh roll 11 are brought together in any desired way, paste having previously been applied to the roll. The web is severed and then begins to run from the roll 11 which is thereafter brought down into running position. This of course is all old so far.

In contact with the outer surface of the roll 12 are provided one or more retarding belts 13. These are mounted on rolls or pulleys 16 on two shafts 14 and 15. Normally this retarding belt and its shaft 15 are not operated by the press in any way but are perfectly idle and are run by the contact of the belt with the roll 12. These belts are mounted on a frame which rests by gravity in such position as to provide this contact.

The press operates a gear 17 meshing with a gear 18 loose on the upper shaft 15. Fast on the shaft 15 is a ratchet wheel 19 and on the gear 18 is a spring pawl 20 for engaging the ratchet wheel.

It will be seen that as the press runs, the gear 18 and ratchet pawl are also rotated, but the belt 13 is already rotating at full speed due to contact with the running roll 12 so it is not operated by the press. The ratchet wheel 19 is rotating with the shaft 15. If, however, the press slows down, or stops suddenly, the ratchet wheel 19 will be prevented by the pawl from having a faster motion than the gear 18. This prevents the pulley, and therefore the belt 13, from running away. As this gear is slowed down by the slowing down of the press, the belt 13 also slows down in proportion and prevents the roll 12 running any faster, thus keeping the tension on the web and holding the web down to a speed exactly as required by the press.

In this way it will be seen that the ordinary feed belt is employed except that these connections are changed. It is operated entirely by the roll 12. But if the press stops or slows down, the ratchet simply acts to hold the belt at the speed of deceleration of the press and slows the paper roll 12 down to rotate in unison with the press. Thus the belt is not a propeller belt but a braking belt. It never speeds

up and never can speed up the roll 12 or the web. It can act only to slow them down. I have spoken in the singular but it is usual to provide two or more of these belts 13 across the web.

Although I have illustrated and described only one form of the invention, I am aware of the fact that modifications can be made therein by any person skilled in the art without departing from the scope of the invention as expressed in the claims. Therefore, I do not wish to be limited to all the details of construction herein shown and described, but what I do claim is:

1. In a web controlling device for a printing press, the combination with means for supporting a running roll and means for guiding the web therefrom to a printing press, of movable braking means for constantly engaging the surface of the running roll, said braking means being normally disconnected from the press and connections from said means to the press for preventing the running roll from rotating any faster at its circumference than the speed of the press.

2. In a web controlling device for a printing press, the combination with means for supporting a running roll and means for guiding the web therefrom to a printing press, of a braking member in contact with the surface of the running roll, and adapted to be propelled solely by said roll, and connections from the press for preventing the running roll from rotating any faster at its circumference than the speed of the web in the press when the press slows down from normal speed.

3. In a web controlling device for a printing press, the combination with a running web and a belt in contact with the surface thereof, of means for supporting the belt to run freely and idly under normal conditions, and means connected with the press for slowing said belt down in proportion to any reduced or decelerated speed of the press at all times.

4. In a web controlling device for a printing press, the combination of a series of belts arranged to contact by gravity with a running web roll, of a shaft, pulleys on the shaft for supporting the belts at one end, whereby the belts will be operated by the running roll, a ratchet wheel fixed on said shaft, a gear loose on the shaft, means for rotating the gear from the press, and a pawl on the gear engaging the ratchet wheel and preventing the rotation of the pulley at a speed greater than that of the ratchet wheel.

5. In a web controlling device for a printing press, the combination with a running web and retarding or braking means in contact therewith, of means for supporting said retarding means to run freely and idly under normal conditions, and means connected with the press for slowing down said retard-

ing means in proportion to any reduced or decelerated speed of the press at all times.

6. In a web controlling device for a printing press, the combination of a belt arranged to contact by gravity with a running web roll, of a shaft, a pulley on the shaft for supporting the belt at one end, whereby the belt will be operated by the running roll, a ratchet fixed on said shaft, a gear loose on the shaft, means for rotating the gear from the press, and a pawl on the gear engaging the ratchet wheel and preventing the rotation of the pulley at a speed greater than that of the ratchet wheel.

7. In a web controlling device for a printing press, the combination with means for supporting a running web roll, of means for pivotally supporting a belt, the pivoted point being so located as to allow the belt to contact with the surface of the running roll by the action of gravity when the running roll is in running web feeding position, whereby the belt will be moved by the running of the roll and its web, and means for preventing the belt from running at all times at a speed greater than that of the web.

In testimony whereof I have hereunto affixed my signature.

HENRY A. WISE WOOD.
